UNITED STATES PATENT OFFICE.

FRANKLIN R. WHITE, OF WATERBURY, CONNECTICUT.

STAPLE.

1,110,091.

Specification of Letters Patent.

Patented Sept. 8, 1914.

Application filed January 9, 1911. Serial No. 601,677.

To all whom it may concern:

Be it known that I, FRANKLIN R. WHITE, a citizen of the United States, and a resident of Waterbury, in the county of New Haven and State of Connecticut, have made and invented certain new and useful Improvements in Staples, of which the following is a specification.

My invention relates to an improvement 10 in staples, and more particularly to that class of staples which are formed from blanks cut or punched from sheet metal, one of the objects being to so shape or form the blanks that they may be cut or punched 15 from metal without any waste thereof, thereby reducing the cost of manufacture.

Another object of my invention is to produce an article of this kind which shall be strong and efficient in use, and which may be 20 used as a button fastener or for any other purpose or purposes for which similar articles are now employed.

With these and other ends in view, the invention consists in certain novel features 25 of construction, as will be hereinafter fully described and pointed out in the claims.

In the accompanying drawings, Figure 1 is a plan view of a strip of metal, showing the manner of cutting the blanks from 30 which the staples are made. Fig. 2 is a plan view of one of the blanks. Fig. 3 is a plan view showing the staple in its first stage of formation. Fig. 3^a is a plan view showing the staple in a die, preparatory to 35 undergoing the next operation. Fig. 4 is a view in elevation showing the staple in its next stage of formation. Fig. 5 is a view taken at right angles to Fig. 4. Fig. 6 is an elevation of the finished staple, and Fig. 40 7 is a plan view of the same.

The manner in which the blanks are cut is indicated in Fig. 1, in which A represents a strip of sheet metal of the desired width, said strip being cut along the parallel 45 inclined lines B, by any suitable means, thus forming the blanks C, said blanks being substantially diamond or lozenge shaped, as shown in Fig. 2. By forming the blank in this manner, as described, it will be seen that 50 all of the metal contained in the strip will be utilized. After the blank has been cut, the ends thereof are subjected to pressure by any suitable means, whereby the metal contained in said ends is pressed or crowded 55 together to form two prongs D, the prongs being rounded and their extreme ends point-

ed to thereby provide prongs, tapering or cone-shaped in form, by a single operation, the central portion E of the blank remaining substantially unchanged in shape, as is 60 shown in Fig. 3. The blank is then placed in a die F, provided with a circular recess G adapted to receive the central portion E of the blank, and recesses H, communicating with said circular recess and adapted to receive the prongs D, as clearly shown in Fig. 3^a. The central portion E is then subjected to pressure in any suitable manner, as for example, by striking the same, whereby the stock or metal of which it is composed will 65 be forced out against the edge of the circular recess G, thus giving to said central portion a rounded configuration.

In the next stage of its formation, the blank is bent into the form shown in Figs. 75 4 and 5, the prongs D extending upward substantially parallel to each other, and the central portion E being curved slightly as shown.

The next and final step consists in flattening or straightening the curved central portion and simultaneously rounding and smoothing the edges thereof, whereby to 80 form the head of the staple in its finished or completed condition, the completed article 85 being clearly shown in Figs. 6 and 7.

It will be seen from the above description that staples consisting of but one piece of metal may be constructed, which will be very cheap to manufacture, and which will 90 be strong, durable and capable of use for all purposes for which similar staples are employed, and in the manufacture of which I avoid any waste or loss of material from 95 which they are made.

My improved staple is especially adapted for the purpose of securing buttons having an imperforate base to a garment. In such cases the base of the button has to be pierced by the points of the prongs in the act of 100 securing the button in place, and an excess of strength is necessary in the prongs in order that they may have sufficient strength to support the point while it is being driven through the imperforate base of the button. 105 This strength secured in my improved staple by making the prongs conical as explained, and prongs are thereby procured which will not be bent in the act of driving the same through an imperforate base button, which 110 is a feature of marked advantage over staples having cylindrical prongs such as

are formed from wire and which have not sufficient strength to prevent them from being bent if it be attempted to force them through the base of an imperforate base but-

ton.
Having fully described my invention, what I claim as new and desire to secure by Letters Patent, is:—

1. A staple made from a blank of sheet metal having the shape of a lozenge, and comprising a head of a single thickness of metal, and two tapering cone-shaped prongs extending at an angle from said head, the diameter of said prongs at their bases being greater than the thickness of the blank from which the staple is formed, substantially as described.

2. A staple made from a blank of sheet metal and comprising a head portion the thickness of which corresponds with the thickness of the blank, and two cone-shaped prongs extending at an angle from said

head portion, the diameter of said prongs at their bases being greater than the thickness of the head portion of the staple, substantially as described. 25

3. A staple made from a blank of sheet metal having the shape of a lozenge, and comprising a rounded head portion, the thickness of which is equal to the thickness 30 of the blank, and two tapering cone-shaped prongs extending at an angle from said head portion, the diameter of said prongs at their bases being greater than the thickness of the blank from which the staple is formed, substantially as described. 35

Signed at Waterbury, in the county of New Haven and State of Connecticut, this fifth day of January A. D. 1911.

FRANKLIN R. WHITE.
